Fig. 6

Fig. 1 is a front perspective view taken from the top and right side of a cabinet for medical electrolysis apparatus, embodying my new design;

Fig. 2 is a front elevational view thereof on a reduced scale, but in closed position;

Fig. 3 is a rear elevational view thereof, as shown in Fig. 2;

Fig. 4 is a right side elevational view thereof, as shown in Fig. 2, the left side being substantially the same as the right side shown;

Fig. 5 is a front elevational view thereof, as shown in Fig. 2, but with all the drawers and doors in their open positions; and

Fig. 6 is a top plan view thereof, as shown in Fig. 5.

The dominant features of my design reside in the full-line portions of the drawing.

I claim:

The ornamental design for a cabinet for medical electrolysis apparatus, substantially as shown and described.
